(57) **CLAIM**

The ornamental design for a hair straightening tool, as shown and described.

DESCRIPTION

FIG. 1 is a top perspective view of a hair straightening tool showing our new design, in an open configuration; FIG. 2 is another top perspective view of the hair straightening tool showing our new design, in a closed configuration;

FIG. 3 is a bottom perspective view of the hair straightening tool as shown in FIG. 1;

FIG. 4 is another bottom perspective view of the hair straightening tool as shown in FIG. 2;

FIG. 5 is a side view of the hair straightening tool as shown in FIG. 1;

FIG. 6 is another side view (inverted) of the hair straightening tool as shown in FIG. 2;

FIG. 7 is a top view of the hair straightening tool as shown in FIGS. 1 and 2;

FIG. 8 is a bottom view of the hair straightening tool as shown in FIGS. 1 and 2;

FIG. 9 is a front end view of the hair straightening tool as shown in FIG. 1;

FIG. 10 is another front end view of the hair straightening as shown in FIG. 2;

FIG. 11 is a rear end view of the hair straightening tool as shown in FIG. 1; and,

FIG. 12 is another rear end view of the hair straightening tool as shown in FIG. 2.

The relatively lighter portions with broken lines in the figures are for the purpose of illustrating portions of the hair straightening tool that form no part of the claimed design.
